CONTAINER AND SHIELDING THEREFOR

Ernest H. Benson, Kansas City, Mo.

Application July 12, 1948, Serial No. 38,227

21 Claims. (Cl. 220—71)

1

The present invention relates in general to the art of shielding objects, and it deals more particularly with the shielding of barrels, drums and similar containers.

The object of the invention, broadly speaking, is to provide a novel form of shielding which is rugged and effective yet simple and economical to manufacture.

A further aim is to provide shielding of the character indicated wherein the object to be protected is resiliently supported and cushioned against shocks.

A further aim is to provide a guard about the object which facilitates handling of the object and which may easily be repaired or replaced whenever damaged through rough handling. The manner in which the guard is secured to the object is an important feature of the invention.

A further aim of the invention is to provide an unique, shock-mounted shipping drum or like container, an important feature residing in the shape or configuration of the container and in the cooperative relationship between the container and the shielding thereabout.

According to the invention I provide a pair of rigid sleeves encircling the opposite ends of the drum, which sleeves are maintained radially spaced from the drum by resilient cushions; the sleeves extend beyond the ends of the drum and are provided with outwardly extending annular beads not only protecting the central section of the drum but also forming rings upon which the drum may be supported and rolled. Novel arrangements are provided for holding the sleeves and the resilient cushioning members in place about the drum.

Other and further objects, together with the novel features of construction by which the objects are achieved, will appear in the course of the following description of the invention.

In the accompanying drawings which form a part of the specification and are to be read in conjunction therewith, and in which like reference numerals are employed to indicate like parts of the various views.

Fig. 1 is an elevational view of a shock mounted shipping drum or barrel embodying the invention, with parts broken away for purposes of illustration.

Fig. 2 is a sectional elevation taken along the line 2—2 of Fig. 1 in the direction of the arrows.

Fig. 3 is an enlarged cross section taken along the line 3—3 of Fig. 1, and

Fig. 4 is an enlarged cross section correspond-

2

ing to Fig. 3 but showing the parts as they are displaced for purposes of assembly or disassembly.

Referring more particularly to the drawings, the drum or barrel 10 is made up of two generally cup-shaped parts 10a and 10b placed mouth-to-mouth and welded together along the annular seam 12. The resultant container is symmetrical about a plane passing through its center normal to the axis of the container, but the weld seam preferably is positioned somewhat off center as shown, so that the larger part 10a will accommodate the bung fitting 14 in a position near the center yet spaced laterally from the weld seam. The ends of the drum are crown-shaped, making it capable of withstanding higher internal pressures than if they were flat, and the side walls curve smooth into the ends, the interior of the container being entirely free of corners and sharp angles such as normally tend to trap sediment and resist cleaning.

Around the opposite ends of the drum, hereinafter sometimes referred to as the head of the drum and the foot of the drum, are circular shields or sleeves 15 and 16. These are larger in diameter than the portions of the drum they encircle, and each is maintained radially spaced from the outside of the drum by an annular cushioning ring 20 seated between complimentary opposed offsets 22 and 24 in the drum and its surrounding sleeve. The cushioning rings are made of deformable resilient material such as neoprene, rubber or the like.

The shields about the head and foot of the drum are connected to one another and held together by longitudinal tie plates 26. These are spaced equally around the mid-section of the drum and, although four are shown, it will be understood that any desired number may be employed. Each tie plate can be secured to the respective shields in any desired fashion, the preferred arrangement being illustrated in the drawings. There it will be seen that the adjacent ends of the sleeves 16 and 18 are flared outwardly with the raw edge 28 on each sleeve rolled smoothly back under the flared portion to conceal same. This forms a reversed annular lip or rim adapted to receive hook-shaped ends 30 provided on the tie plates, as shown. At the same time, the flared portion forms a rounded annular bead 32, the beads on the two shields serving together as rolling rings to support the drum and facilitate rolling thereof when its axis is horizontal.

The opposite or outer-most end of each shield

is provided with a rolled rim 34 reinforcing the shield and concealing the raw edge. These rims lie in planes normal to the axis of the drum and beyond the rounded ends of the drum.

Attachment of the tie plates 26 to the end shields is effected by forcing the two shields axially toward one another in a suitable press or jig, not shown. This deforms the resilient cushioning rings as indicated in Fig. 4 and permits the hooks 30 on the tie plates to be passed over lip 28. When properly positioned the pressure on the end shields is released whereupon the cushioning rings return to their normal shape forcing the shields apart and causing the hooks 30 to be retained or locked on the lip 28 in the manner shown in Fig. 3.

Thus assembled, the cushioning rings serve to maintain the parts in interlocked condition and also serve to resiliently support the barrel or drum 10 in spaced relation to the end shields and tie plates. The shields extend beyond the ends of the drum, guarding same against injury due to dropping or other rough treatment, while the rolling rings similarly protect the central section of the vessel. Accordingly even though abuse and rough handling are to be expected, it nevertheless is feasible to make the drum of material having little inherent resistance of impact; for example, there may be employed a metal such as magnesium which is desirable because of its lightness and, at times, because it is chemically inert as to the material which it is desired to carry in the container. The shields 16 and 18 naturally are made of stronger material such as steel.

If either end shield should become dented in use, it may easily be removed for repair, or a fresh shield may at once be substituted therefor in order to minimize the time that the drum is out of service. Removal is effected simply by forcing one end shield toward the other (see Fig. 4) until the hook shaped ends 30 of the tie plates can be freed from the inwardly turned lip or rim 28, the damaged end piece then being withdrawn from the drum. The manner in which the same or another shield subsequently is reattached to the tie plates has already been described.

The use of shields which extend beyond the ends of the drum and which provide rolling rings therefor makes it possible for the drum to have crown-shaped ends and to be free of corners and sharp angles tending to trap sediment and foreign matter. Thus the vessel is easy to clean and to maintain clean. Although the ends are outwardly dished or dome shaped, the assembled unit will stand on end supported by the shield; and one drum may easily be stacked on another.

Each cushioning ring 20 is provided with drain slots 36 in order to prevent moisture or sediment from collecting in the annular space within the upper sleeve when the barrel stands on end. This is important in that it prevents distortion due to freezing of moisture between sleeve and drum, and minimizes rusting or other corrosive action.

From the foregoing it will be seen that the objects of the invention have been accomplished, the structure disclosed being well adapted to attain all the aims and ends hereinbefore set forth and having other advantages which are obvious and which are inherent to the structure.

It will be understood that certain features and subcombinations are of utility and may be employed without reference to other features and subcombinations. This is contemplated by and is within the scope of the appended claims.

Inasmuch as various modifications of the invention may be made without departing from the scope thereof, it is to be understood that all matter herein set forth or shown in the accompanying drawings is to be interpreted as illustrative and not in a limiting sense.

Having thus described the invention, I claim:

1. In combination, a container, a pair of sleeves encircling opposite ends of the container, means on the container holding the sleeves apart in axially spaced relation, a plurality of longitudinal tension links bridging the space between the two sleeves, said links spaced circumferentially about the container and each link having its opposite ends detachably connected to the respective sleeves to prevent same from moving apart said holding means comprising opposed parts on said container and sleeves, and a resilient deformable buffer between said parts.
2. A combination as in claim 1 wherein at least one of the sleeves projects beyond the end of the container.
3. A combination as in claim 1 wherein the spaced inner ends of the two sleeves are flared radially to provide rolling rings for the container.
4. In combination, a container, a pair of sleeves encircling opposite ends of the container, means on the container holding said sleeves in axially spaced relation, the spaced inner ends of the sleeves being flared radially outward with the extreme edge of each sleeve doubled back under the flared portion, and tension links between two sleeves preventing them from moving apart, each link having hook-shaped ends adapted to hook over the doubled back edge of the sleeves.
5. A combination as in claim 4 wherein said holding means comprises opposed parts on said container and sleeves and a resilient deformable buffer between said parts.
6. In combination, a container, a pair of axially spaced sleeves encircling opposite ends of the container, resilient spacers between the sleeves and container to maintain the sleeves radially spaced from the container, each spacer engaged on the side farthest from the center of the container by a shoulder on the sleeve and engaged on the side nearest the center of the container by a shoulder on the container, and a plurality of longitudinal tension links bridging the space between the two sleeves, said links spaced circumferentially about the container and each link having its opposite ends detachably connected to the respective sleeves to prevent same from moving apart.
7. A combination as in claim 6 wherein each sleeve has a radially projecting annular bead forming a rolling ring for the container.
8. In combination, a container, a sleeve encircling one end of the container, resilient spacing means between said sleeve and said container to maintain the sleeve radially spaced from the container, said means engaged on the side nearest the end of the container by a shoulder on the sleeve and engaged on the side nearest the center of the container by a shoulder on the container, longitudinal tension links circumferentially spaced about the container, each link detachably connected at one end to said sleeve, and a connection between the container and the other end of each link anchoring the links against longitudinal movement toward said one end of the container.
9. A combination as in claim 8 wherein the connection between each link and the sleeve comprises interlocking hooks on the link and sleeve.

10. A combination as in claim 8 wherein said sleeve projects beyond the end of the container.

11. In combination, a container having an enlarged central portion with an annular offset on either side thereof, a pair of sleeves encircling the opposite ends of the container, each sleeve having an annular offset opposed to one of the annular offsets on the container, a pair of rings of resilient deformable material each confined between one pair of opposed offsets, and means linking the two sleeves to one another.

12. A combination as in claim 11 wherein the spaced inner ends of the two sleeves are flared radially to provide rolling rings for the container.

13. A combination as in claim 11 wherein at least one of the sleeves projects beyond the end of the container.

14. A combination as in claim 11 wherein each of said rings contains drain apertures at spaced intervals about its circumference.

15. In combination, a container, a pair of spaced apart sleeves encircling opposite ends of the container, a plurality of tension links spaced circumferentially around the container, each link bridging the space between said sleeves and having hooks at its opposite ends, means on each sleeve to receive said hooks, and resilient members between the respective sleeves and the container maintaining the sleeves spaced away from the container and urging said sleeves away from one another thereby to maintain said hooks engaged with said receiving means.

16. A combination as in claim 15 wherein said tension links are spaced radially away from said container.

17. In combination, a container, a pair of spaced apart sleeves encircling opposite ends of the container, hooks on said sleeves, a plurality of tension links spaced circumferentially around the container, each link bridging the space between said sleeves and having means at its opposite ends to receive said hooks on the respective sleeves, and resilient members between the respective sleeves and the container maintaining the sleeves spaced away from the container and urging said sleeves away from one another thereby to maintain said hooks engaged with said receiving means.

18. A combination as in claim 17 wherein said tension links are spaced radially away from said container.

19. In combination, a container having an enlarged central portion and smaller end portions each separated from the central portion by an annular offset, a pair of spaced apart sleeves encircling the respective end portions of the container, the inner ends of said sleeves being flared radially outward over said offsets, a plurality of

tension links spaced circumferentially around the enlarged central portion of the container, each link bridging the space between said sleeves and having hooks at its opposite ends, means on each sleeve to receive said hooks, and a pair of resilient deformable rings each confined between one of said offsets on the container and the superposed flared portion of one sleeve, said rings maintaining said sleeves spaced radially from the container and urging the sleeves away from one another thereby to maintain said hooks engaged with said receiving means.

20. In combination, a container having an enlarged central portion and smaller end portions each separated from the central portion by an annular offset, a pair of spaced apart sleeves encircling the respective end portions of the container, the inner ends of said sleeves being flared radially upward over said offsets and having hooks formed thereon, a plurality of tension links spaced circumferentially around the enlarged central portion of the container, each link bridging the space between said sleeves and having means at its opposite ends for receiving said hooks on the respective sleeves, and a pair of resilient deformable rings each confined between one of said offsets on the container and the superposed flared portion of one sleeve, said rings maintaining said sleeves spaced radially from the container and urging the sleeves away from one another thereby to maintain said hooks engaged with said receiving means.

21. In combination, a container, means shielding said container on all sides, said means consisting of a plurality of separable shield elements covering different parts of the container, inter-linked hooks on the several shield elements to connect them together, and resilient spacers between certain of the elements and the container maintaining said elements spaced apart from the container at all points, said resilient spacers also applying forces on said shield elements to maintain said interlinked hooks under tension.
